(57) **CLAIM**

I claim the ornamental design for a power connection panel, as shown and described.

DESCRIPTION

FIG. 1 is a front, top and side perspective view of a power connection panel in use condition, showing my new design;
FIG. 2 is a front elevational view thereof;
FIG. 3 is a back elevational view thereof;
FIG. 4 is a top plan view thereof;
FIG. 5 is a bottom plan view thereof;
FIG. 6 is a left side elevational view thereof; and,
FIG. 7 is a right side elevational view thereof.
The broken line in the figure drawing view represents unclaimed environment only and forms no part of the claimed design.
